UNITED STATES PATENT OFFICE.

WILLIAM WILLARD KELLY, OF CLEVELAND, OHIO.

DISPLAY SALES RACK.

Application filed May 21, 1924. Serial No. 714,871.

This invention relates to a display sales rack for counter use, which is in some respects similar to the rack disclosed in my pending application, Serial Number 694,064, filed February 20, 1924, but embodies certain improvements which adapt it especially to the display of packages of chewing gum, mints, and other articles which may be put up for sale in a similar form.

10 The general object of the present invention is to provide an inexpensive and practical device comprising a number of carriers for holding goods of the nature specified, in such a manner that they will be displayed to the best possible advantage. The rack contains a concealed bell or similar alarm, and improved means are provided to increase its activity or sensitiveness. The carriers radiate from a common center about which they 20 revolve as a unit, and they are specially constructed with a view to facilitating the insertion or removal of the goods, at the same time making it impossible to effect the removal without sounding the alarm.

25 The invention also includes various other structural details which will be particularly described in the following detailed description taken in connection with the accompanying drawings, illustrating the preferred form thereof.

In the drawings:

Figure 1 is a perspective view of the invention.

Figure 2 is a central vertical section thereof.

Figure 3 is a horizontal section taken on the line 3—3 of Figure 2.

As illustrated in the drawings, the device comprises a broad base 10, which may be stamped from thin metal, or constructed in any other desired manner, and which supports a central vertical shaft 11, on which the display rack is revolvably supported. For this purpose a collar 12 is mounted on 40 the shaft 11, and supported by means of a pin 13 or the like. The rack comprises a body portion 14, preferably in the form of a cylindrical shell, having a top 15, and a bottom 16 secured to its ends by tongues 17, 45 or other suitable means. The upper end of the shaft 11 extends centrally through the top 15, and constitutes an axis about

which the rack may revolve. The end 18 is preferably slotted to receive the foot 19 of a frame 20, which is adapted to contain a 55 card 21 bearing a trademark or other advertising matter, the foot 19 being secured by a pin 22 or the like.

A plurality of radiating wings or carriers 23 are supported in symmetrical relation to 60 the shell 14, and may be suitably secured thereto by tongues 24, or in any other desired manner. These carriers 23 are rectangular in shape, and of a suitable size to receive a number of packages of chewing gum, 65 mints or the like, which may be either rectangular or cylindrical in shape, as illustrated at 25 and 26, respectively. Each of the carriers 23 is in the form of a skeleton frame, each of its opposed faces being 70 formed by a peripheral flange 27, and the remainder being open so that all except the ends of the packages may be visible from either side of the carrier. The top and bottom of the carrier are closed, and the outer 75 wall is closed except at the lower end where it is cut away, as indicated at 28, to provide an opening through which a single package may be inserted or removed from the bottom of the carrier, as shown at 29. When 80 inserting a package in this manner, the packages already in the carrier are lifted up, and the succeeding package inserted beneath the same. Thumb notches 30 are preferably cut in the flanges 27, so that the packages within the carrier may be easily grasped and lifted. Thumb notches 31 are also cut so 85 that the end of the package may be easily grasped for removing the same. While it is necessary, in filling the carrier to its capacity, to insert the last packages through the opening 28, the lower part of the carrier may be filled directly through the face of the carrier by inserting the packages at an angle, as illustrated at 32. (Fig. 1.) 90

In order to prevent theft, as well as to attract the attention of customers and promote sales, a concealed alarm is provided which will become audible upon the slightest movement of the rack. For this purpose, 100 a plurality of loops 33 are struck downwardly from the top 15, and serve to support clappers 34 which are arranged in close proximity to a bell or chime 35, secured to

the shaft 11. In order to make the alarm more sensitive, the bottom 16 of the shell 14 is cut away centrally, as indicated at 36, (Fig. 2) so as to permit a certain amount 5 of lateral play to the lower part of the shell. The upper surface of the collar 12 is convex, and the entire shell 14 and the carriers 23 are supported from the top 15, which rests upon the convex surface of the collar, thus 10 forming a bearing from which the carriers are suspended, and about which they may oscillate laterally whenever subjected to the slightest touch. Series of openings 37 are preferably provided in the shell 14, so that 15 the sound may be more readily emitted.

From the foregoing description, it will be noted that the packages of goods are held so that both sides are displayed, only the ends being concealed. The rack is suspended on 20 the collar 12, so that the slightest touch will cause it to oscillate and bring one of the clappers into contact with the bell. It will be impossible to remove a package without rendering the alarm audible. The packages 25 may be easily inserted in or removed from the carrier when desired, but can not become accidentally dislodged.

While I have shown and described specifically the construction of the various features which constitute the preferred form 30 of the invention, it is obvious that many modifications may be made therein without departing from the salient features thereof, and it is, therefore, my intention to include 35 all such modifications within the scope of the appended claims.

What is claimed is:

1. In a display device, the combination of 40 a base having a shaft secured to and extending upwardly therefrom, a bearing member supported by the shaft near its upper end, a hollow body surrounding the shaft with its 45 top resting on said bearing member and constituting a support for said body, said body containing compartments for receiving small packages for display, the bottom of the body having an opening larger than the shaft, whereby to permit lateral oscillation of said body, and means within the body operable to 50 sound an alarm upon slight oscillation of said body.

2. In a display device, the combination of 55 a vertical shaft, a collar supported on the shaft and having a convex upper face, a hollow body surrounding the shaft and having a top resting on the convex face of said collar with the remainder of the body depending from said top and containing compartments for receiving small packages for 60 display, the bottom of the body having an opening larger than the shaft so as to permit lateral oscillation of the body about said collar, and means within the body operable to 65 sound an alarm when the body is so oscillated.

3. In a display device, the combination of a base having a shaft secured to and extending upwardly therefrom, a hollow body mounted to revolve about said shaft, a bearing member supported by the shaft near its 70 upper end in supporting relation to the top of said body, the remainder of the body being disposed in depending relation to the top, said body containing compartments for receiving small packages for display, the 75 bottom of the body having an opening larger than the shaft so as to permit lateral oscillation of the body, a bell secured to the shaft within the body, and clappers suspended from the upper end of the body in close 80 proximity to the bell, whereby to sound the bell upon slight oscillation of the body.

4. In a display device, the combination of a body member comprising a hollow shell with an opening in the center of its bottom, 85 a vertical shaft extending through said opening, means supported by the shaft on which the top of the body rests, the remainder of the body being in depending relation to its top, said body containing compartments for 90 receiving small packages for display, said supporting means constituting the sole support for the body, the opening in the bottom through which the shaft extends being larger than the shaft to permit the body to oscillate 95 about its support, and means operable to sound an alarm when the body is so oscillated.

5. In a display device, the combination of 100 a central body member having radially projecting rectangular skeleton carriers adapted to contain small packages, each of the opposed faces of said carriers being open except at the edges so as to display both sides of the packages, the top and bottom of the 105 carrier being permanently closed, and the outer side closed except at the lower edge which is cut away sufficiently to permit the insertion or removal of the packages one by one, the upper portions of the opposed lower 110 side faces having thumb notches cut therein to permit the lowermost package to be grasped and lifted within the carrier and the lower portions of the opposed front side faces having thumb notches to permit the 115 lowermost package to be grasped and withdrawn through the opening in the outer side.

6. In a display device, the combination of 120 a central hollow body member supported for rotation about a vertical axis and also for lateral swinging movement, a plurality of skeleton carriers projecting radially from the central body member and adapted to contain small packages, and means within the body member operable to sound an alarm 125 upon slight rotatory or swinging movement of said body member.

7. In a display device, the combination of 130 a vertical shaft, a hollow body member supported for rotation about said shaft and also

for lateral swinging movement, said body member having radially projecting carriers provided with means for supporting small packages so that opposite sides thereof are visible, a bell secured to the shaft within the body member, and clappers suspended from the upper end of the body member in close

proximity to the bell, whereby to strike the same upon slight rotatory or swinging movement of said body member. 10

In testimony, that I claim the foregoing as my own, I have hereunto affixed my signature.

WILLIAM WILLARD KELLY.
